US0D1082724S

(12) **United States Design Patent** (10) **Patent No.:** **US D1,082,724 S**
(45) **Date of Patent:** **** Jul. 8, 2025**

(54) **SELF-POWERED WIRELESS SWITCH**

(71) Applicant: **Eaton Intelligent Power Limited**,
Dublin (IE)

(72) Inventors: **Alex Zhuang**, Shanghai (CN); **George Zhang**, Shanghai (CN); **Erik Jeffrey Gouhl**, Fayetteville, GA (US); **Harry Zhang**, Shanghai (CN); **Andrew Yang**, Jiangsu (CN); **Darron Kirby Lacey**, Peachtree City, GA (US); **Tom Xiong**, Shanghai (CN)

(73) Assignee: **EATON INTELLIGENT POWER LIMITED**, Dublin (IE)

(**) Term: **15 Years**

(21) Appl. No.: **29/941,882**

(22) Filed: **May 13, 2024**
